S. BUCHSBAUM,
SWITCH MOVEMENT.
APPLICATION FILED JULY 21, 1917.

1,295,966.

Patented Mar. 4, 1919.

UNITED STATES PATENT OFFICE.

SAMUEL BUCHSBAUM, OF CHICAGO, ILLINOIS, ASSIGNOR TO GORDON ELECTRIC AND MANUFACTURING CO., OF WATERVILLE, CONNECTICUT.

SWITCH-MOVEMENT.

1,295,966.

Specification of Letters Patent.

Patented Mar. 4, 1919.

Application filed July 21, 1917. Serial No. 181,967.

To all whom it may concern:

Be it known that I, SAMUEL BUCHSBAUM, a citizen of the United States, residing at Chicago, in the county of Cook and State of Illinois, have invented a certain new and useful Improvement in Switch-Movements, of which the following is a full, clear, concise, and exact description, reference being had to the accompanying drawings, forming 10 a part of this specification.

My invention relates to switch movements and is more particularly an improvement over the switch movement described and claimed in my prior Patent No. 1,222,355, 15 dated April 10, 1917.

My invention concerns itself with the simplification of the general style of movement set forth in my said patent. The invention herein disclosed sets forth a movement which 20 contains but two moving parts exclusive of the finger piece which operates the moving parts. In the preferred form, one of the above parts is spring pressed.

I will explain this particular form of 25 carrying out my invention more in detail by referring to the accompanying drawing, in which—

Figure 1 is a longitudinal sectional view of the device constructed in accordance with 30 my invention;

Fig. 2 is a top view of the device;

Fig. 3 is a sectional view on line 3—3 of Fig. 1 with the finger pieces removed;

Fig. 4 is a sectional view on line 4—4 of 35 Fig. 3;

Fig. 5 is a fragmentary view similar to Fig. 1 showing the movement in its reverse position, and

Fig. 6 is a perspective view of the insulating shell, showing the two contact terminals mounted in position.

In the embodiment herein shown my switch movement is illustrated as of use for what is commonly called a pendant switch, 40 the switch movement being mounted in a shell consisting of the base plate 1 and cap 2. This switch movement comprises the insulating support 3 having a central recess 4 and having two side recesses 5 and 6 within 45 which circuit controlling springs 7 and 8 are mounted, the same being held in place by screws 9, 10, which screws extend through the insulating piece 3 and hold the connecting terminal strips 11 and 12. These terminal strips carry connecting screws 13 and 55

14. The means for making and breaking the circuit between the springs 7 and 8 consist of a circuit changing element 15 mounted at the extremity of a link 16 slidably and loosely carried on an extension 17 of a base piece 18. This extension 17 has the aperture 19 through which the link 16 is movable. A spring 20 normally forces the switch element away from the standard 17 and against the rocking link 21. Said 60 link 21 through the agency of a centrally located aperture 24 is placed upon the stud 25, which stud forms part of the arm 26. This arm 26 is also part of the base piece 18. The rocking link 21 has the limits of its 65 motion set by lugs 27, 27 forming part of upwardly projecting shelves 28, these shelves likewise being part of the base piece 18. Screws 29 hold the switch structure in position in the insulating base 3. Finger pieces 70 30 and 31 united by the stem 32 act upon the lower portion of the rocking link 21 to push it first toward one side and then toward the other. This stem 32 projects through the opening 33 in the link 21. These finger 75 pieces 30 and 31 project outwardly of the shell, as clearly apparent from the illustration.

The link 21 at its upper extremity is bifurcated to form wings 23, 23 which are on 80 opposite sides of the stem 32. The lower protruding surfaces of these wings serve as stops for the switch element 15 when in one of its limiting positions (see Fig. 5). The lower extremity of the link 21 has turned-in 85 lugs 22 which serve as steps for the switch element 15 when in its other limiting position.

From the above description it will be readily seen that there are but three moving 90 parts in the entire structure. One of these is the link 16 and the other is the rocking link 21, the link 16 at the same time carrying the circuit controlling element 15. The finger pieces merely act on one extremity of the rocking link 21, thereby causing the spring pressed link 16 to change its position by snap action from one limiting position to the other.

In the particular form shown the spring 100 20 and link 16 which it controls are made in two parts as illustrated. The base piece 18 is made from a single piece of metal which has supporting means for the movable links and also means to control the limit of mo- 110

tion. The insulating support 3 is likewise made of one piece and to it the switch movement is held by the two screws 29 which need not perform any other function than 5 that of holding the parts together. As will be apparent from the illustration there is ample room for the connecting terminals to which the incoming wires may be attached.

The improved construction of the shell 10 herein is not explained in detail as the same is made the basis for a separate application for Letters Patent Serial No. 181,966 filed July 21, 1917.

Having thus described one form which 15 my invention may take it is thought the invention will be clear to those skilled in the art, and what I claim as new and desire to secure by Letters Patent is:

1. In a switch movement of the character 20 described the combination with a base piece, a rocking link pivotally carried by said base piece, a second link oscillatingly and shiftably carried by said base piece at one extremity of said second link and having its 25 other extremity movable along said rocking link, a switch controlling element forming an integral part of said second aforesaid link, manually controlled means for moving said rocking link from one limiting position 30 toward its other limiting position, said rocking link having sidewise extending projections at one end and inwardly bent pro-

jections at the other to limit the movement of said second link, and resilient means associated with said second link tending to 35 move said link toward either of its extreme positions.

2. In a switch movement of the character described the combination with a base piece, a rocking link pivotally carried by said base 40 piece, a second link oscillatingly and shiftably carried by said base piece at one extremity of said second link and having its other extremity movable along said rocking link, a switch controlling element forming 45 an integral part of said second aforesaid link, said switch element and said second link consisting of a substantially T shaped structure the extremities of whose arms are bent inwardly to form said switch element, 50 manually controlled means for moving said rocking link from one limiting position toward its other limiting position, said rocking link having sidewise extending projections at one end and inwardly bent projections at the other to limit the movement of 55 said second link, and resilient means associated with said second link tending to move said link toward either of its extreme positions.

In witness whereof, I hereunto subscribe my name this 2nd day of July, A. D., 1917.

SAMUEL BUCHSBAUM.
